UNITED STATES PATENT OFFICE.

CECIL C. ABBOTT, OF HARBOR SPRINGS, AND WILLARD EARL BASSETT, BERT L. BASSETT, AND IRVIN L. BASSETT, OF DETROIT, MICHIGAN.

FIRE ESCAPE.

Application filed February 24, 1921. Serial No. 447,423.

To all whom it may concern:

Be it known that we, CECIL C. ABBOTT, WILLARD E. BASSETT, BERT L. BASSETT, and IRVIN L. BASSETT, citizens of the United States, the first named residing at Harbor Springs, in the county of Emmet, and the others at Detroit, in the county of Wayne, and State of Michigan, have invented certain new and useful Improvements in Fire Escapes, of which the following is a specification.

This invention relates to portable fire escapes which may be anchored within a room when use of the same is necessary and operated to lower a person from a window of the room to the ground. The object of our invention is to provide novel means for preventing excess speed in descent so that the person compelled to use the device will not be apt to be injured by violent contact with the ground. The invention resides in certain novel features which are illustrated in the accompanying drawings and hereinafter fully set forth.

In the drawings—

Fig. 1 is a side view with parts broken away;

Fig. 2 is an end elevation with parts in section.

In carrying out our invention, we employ an outer casing 1 which is provided with an eye or hook 2 adapted to be engaged over a bedpost or some fixed object adjacent a window of a room. This casing is provided at a point diametrically opposite the hook or eye 2 with a slot 3 through which the tape or cable 4 passes, the said tape or cable being equipped at its free end with a belt to be passed around the body of the person using the escape. The wound tape is carried by a drum 5 and has its inner end secured to the hub of the drum, said hub being keyed to one end of the main shaft 7 which has its ends supported in the walls 8 of a supporting frame and also has its intermediate portion rotatably mounted in a partition or plate 9 forming a part of the supporting frame. The partition 9 divides the casing into a tape or cable chamber containing the drum 5 and the cable 4 and a working chamber containing the operating mechanism. At that end of the shaft 7 which is disposed within the working chamber, a ratchet wheel or collar 10 is fitted upon the shaft so that it may slide longitudinally of the same but is

constrained to rotate therewith and a spring 11 is coiled around the shaft 7 between the said ratchet and the adjacent side plate 8. This ratchet 10 engages a mating ratchet 12 which is fast to a gear wheel 13 fitted loosely upon the shaft 7, as shown, a pinion 14 being arranged concentric with the shaft between the said gear 13 and the partition 9 and secured to the hub of the drum. The gear wheel 13 meshes with a pinion 15 which is carried by a countershaft suitably journaled in the plate 8 and the partition 9, said countershaft also carrying a gear wheel 16 which meshes with a pinion 17 on the governor shaft 18. The said governor shaft is journaled in the partition 9 and in the inner end wall of a governor casing or drum 19, the peripheral wall of the casing being secured rigidly to the plate 8, and a disk or head 19' being carried by the end of the shaft 18 within the casing. Shoes 20 are carried by the outer ends of shanks 21 which are provided with longitudinal slots 22 engaged by headed studs or pins 23 fitted through the slots into the disk or head 19' so that the shanks will be supported within the casing and permitted to slide toward and from the periphery of the same. The shoes 20 are provided with arcuate outer edges corresponding to the peripheral wall of the governor casing and are normally out of contact with said peripheral wall. Pivoted upon the disk 19', adjacent each shank 21, is a dog 24 pivoted at one end to the adjacent shank 21, as shown at 25, and having its other end formed into a hook or tooth 26. Governor arms 27 are pivoted upon the disk 19' and these governor arms are provided with hooks 28 at their outer extremities adapted to engage the hooks 26, as clearly shown, while at their opposite ends they carry the weights 29 connected by a spring 30 and normally drawn toward each other by said spring. When the device is in use, the unwinding of the tape or cable 4 will impart motion to the shaft 7 and this motion will be transmitted through the described gearing to the governor shaft 18 and inasmuch as said shaft is fixed to the disk 19' said disk will be rotated at the same speed as the shaft. As the speed increases, the weights 29 will move apart under centrifugal action and the governor arms 27 will be rocked upon their fulcrums, thereby causing the hooks or teeth 28 to swing in-

wardly and bear upon the hooks or teeth 26 so as to rock the dogs 24 and thereby slide the shanks 21 outwardly to cause the shoes 20 to bear upon the peripheral wall of the 5 governor casing. The speed of the parts will, therefore, be checked and the person using the device will be lowered gradually to the ground so that he will not be injured through too rapid descent and sudden contact with the ground. When the cable 4 is 10 rewound, the ratchet member 10 will work loosely upon the ratchet member 12 and ride over the same so that the governor will not be operated.

15 To rewind the cable or tape 4, we provide a spring 31 which is wound as the tape or cable 4 is drawn from the casing. The spring 31 has one end anchored within the casing, as shown at 32, and its other end is 20 secured to the shaft 33 about which the spring is wound. A gear 34 is also secured to the shaft 33 and this gear 34 meshes with a pinion 35 which is fast to a shaft 36 mounted in the partition 9 and the side plate 25 8 and upon the same shaft 36 is a gear 37 which meshes with a gear 38 upon a shaft 39 mounted in the partition 9 and the side plate 8 in the same horizontal plane as the main shaft 7, a gear 40 being also secured 30 upon the shaft 39 and meshing with the pinion 14 upon the main shaft. It will thus be seen that when the shaft 7 is rotated by the descending or unwinding tape or cable 4, the motion is transmitted to the gear 34 35 so as to wind the spring 31 and immediately upon the cable being relieved of the weight of the person who used the device the spring 31 will expand and tend to unwind and thereby actuate the described gearing in the 40 opposite direction so that the cable will be rewound within the drum 5 and the belt or other support carried by the cable will be drawn upwardly from the ground to the

window of the room in which the device is located so that it may be used by another 45 person.

It will be readily noted that we have provided a very compact, simple and efficient device which may be readily used by unskilled persons and which may be manufactured at a low cost. The governor will effectually retard the descent of the person using the device and acts with the same efficiency whether the escaping person is light 50 or heavy. When the cable is being retracted, the governor is not actuated so that the work required of the spring 31 is minimized and no check is put upon the rewinding of the cable to delay the second use of the apparatus. 55

Having thus described the invention, what is claimed as new is:

The combination of a main shaft, means for rotating said shaft, a governor comprising a stationary peripheral wall, a rotatable 65 disk, gearing connecting said disk with the main shaft for rotation in one direction, governor shoes slidably mounted upon said disk and adapted to engage the peripheral wall, dogs each pivotally mounted between 70 its ends upon said disk and pivotally attached at one end to the shank of the adjacent governor shoe, the opposite ends of the dogs being free and having hooked terminals, and governor arms mounted upon the 75 disk for rocking movement and provided with hooks engaging under the free ends of the dogs whereby to actuate the said dogs and move the shoes outwardly.

In testimony whereof we affix our signatures. 80
